UNITED STATES PATENT OFFICE.

HARRY FULLER, OF CLEVELAND, OHIO, ASSIGNOR TO THE KING BRIDGE COMPANY, OF CLEVELAND, OHIO, A CORPORATION OF OHIO.

END SUPPORT FOR LOCOMOTIVE TURN-TABLES.

No. 823,405.

Specification of Letters Patent.

Patented June 12, 1906.

Application filed March 5, 1906. Serial No. 304,184.

To all whom it may concern:

Be it known that I, HARRY FULLER, a citizen of the United States, residing at Cleveland, in the county of Cuyahoga and State of Ohio, have invented a certain new and useful Improvement in End Supports for Locomotive Turn-Tables, of which the following is a full, clear, and exact description.

The object of the present invention is to provide an end support for a locomotive turn-table which shall be able to withstand the shocks received from the heavy modern locomotives.

The invention resides particularly in so dividing and mounting the end supports that the shock of the oncoming engines shall be distributed between the supporting units and in such manner as to cause a minimum distortion of the supporting-frames, and consequently decrease the liability of binding action between the supports and the circular trackway.

Referring to the accompanying drawings, Figure 1 is a side elevation of part of a locomotive turn-table. Fig. 2 is a plan view of same. Fig. 3 is an end elevation. Fig. 4 is a cross-section partly broken away near the center.

The table A is, as usual, supported centrally upon the usual steel plates A' and rollers A², permitting it to be swung horizontally and tilt slightly in a vertical plane and does not present any novelty which I desire to claim in this application, consisting of the usual framework provided with bracing - girders. At each end of the table, however, where there has heretofore been rigidly secured a truck-frame having journaled therein four supporting-wheels I provide a pair of supporting-frames B D, one mounted at each side of the table end and each journaled in such manner as to freely oscillate in a vertical plane without regard to the movement of the table. Since each of these supporting-frames B D may oscillate in a vertical plane without regard to the movement of the table, it is plain that the oscillation of each is independent of that of the other. This is of primary consequence in attaining the results sought by this invention. As is well known, these end supports of turn-tables normally do not touch the circular track C of the pit until a locomotive is run thereon, the entire weight of the table, if properly constructed, being

borne by the central support. This produces a condition not ordinarily occurring in any other supporting structure—namely, one of normal instability—and renders it subject to wearing shock on every occasion of its use. As locomotives pass thereon the end of the turn-table receives a sudden downward blow, the entire force of which is directed onto the end supports. Where these end supports have been rigid, as in the turn-tables heretofore constructed, any inequality in the level of the track at that point results in uneven wear on the wheel-bearings and frequently in distortion of the frame, which results in the binding action between the wheels and the circular track, as aforesaid. For example, suppose the two outside wheels of the rigid truck to be the first to come in contact with the trackway. The result will be that the entire load will be borne by these two wheels, and the resulting strain will tend to distort the truck, so as to cause it to sag in the center. This happens more readily than one would think to be the case, owing to the enormous weight suddenly thrown upon the structures. As will be plainly evident, any distortion of the frame whatever produced in any manner is likely to throw the wheels out of alinement, so that upon their movement about the circular track they will bind thereagainst and make it difficult to operate the table. In the structure which I have devised it will be plain that should the two outer wheels B' D' be the first to come in contact with the track, owing to any inequalities in the latter, the support of each of these outer wheels will yield in an oscillatory manner until the inner wheels B² D² also reach the track, thus distributing the blow given by the locomotive between the four points of support to which the structure is designed to transmit such blows.

This structure is to be plainly distinguished from those cases in which divided trucks in traveling carriers are used for their equalizing effect, since the conditions which obtain in the apparatus under consideration are not found in the moving carriers. While it is true that these supports do operate as equalizing-trucks during the movement of the turn-table, it is not for this purpose that they are applied, and for this purpose alone they would be ordinarily a superfluous luxury. It is because the end supports of locomotive

turn-tables of necessity receive such sudden and enormous vertical blows that this structure has a unique utility, and it is in its function in distributing such blows to the proper points that its value resides.

Having thus described my invention, I claim—

1. A locomotive turn-table having an end support comprising two independent truck-frames, each pivotally mounted so as to be capable of vertical oscillation.

2. A locomotive turn-table having an end support comprising a pair of independent trucks, each pivotally mounted to the table-frame, and each having a supporting-wheel on each side of its supporting-pivot. 15

In testimony whereof I hereunto affix my signature in the presence of two witnesses.

HARRY FULLER.
